UNITED STATES PATENT OFFICE

JOHN MOORE, OF DETROIT, MICHIGAN, ASSIGNOR, BY MESNE ASSIGNMENTS, TO ANDREW RUEN HANGER CO. INC., A CORPORATION OF MICHIGAN

FORMING MACHINE

Application filed March 1, 1930. Serial No. 432,322.

My invention relates to a new and useful improvement in a forming machine and in the specific embodiment shown I have illustrated the invention applied to a forming machine in which the device is adapted for forming garment hangers from wire and similar bendable material. It is an object of the present invention to provide in a forming machine of this class a forming mechanism mounted on a rotatable carrier and operable for effecting its forming operations upon rotation of said carrier.

Another object of the invention is the provision in a forming machine of this class of a forming mechanism mounted on a rotatable carrier and cam operated for performing its forming operations upon rotation of said carrier.

Another object of the invention is the provision of a forming mechanism of this class whereby the material operated upon is primary to the main forming operation offset intermediate its ends and fixedly bound in position.

Another object of the invention is the provision in a forming mechanism of this class of a feeding mechanism for feeding the material operated upon into the forming mechanism while the same is being rotated without interrupting the rotation thereof.

Another object of the invention is the provision in a forming machine of this class of a feeding mechanism for feeding the strips of material to be formed individually to the forming mechanism.

Another object of the invention is the provision in a forming machine of this class of a twisting mechanism and a hook forming mechanism operated by cams upon the rotation of the carrier on which the forming mechanism is mounted.

Another object of the invention is the provision of a forming machine of this class which will be simple in structure, economical of manufacture, efficient and rapid in use, and durable.

Other objects will appear hereinafter.

The invention consists in the combination and arrangement of parts hereinafter described and claimed.

The invention will be best understood by a reference to the accompanying drawings which form a part of this specification and in which,

Fig. 1 is a side elevational view of the invention. 55

Fig. 2 is an end elevational view of the invention.

Fig. 3 is a view taken on line 3—3 of Fig. 1.

Fig. 4 is a bottom plan view of one of the forming mechanisms with parts broken away and parts shown in section, taken on line 4—4 of Fig. 3. 60

Fig. 5 is a fragmentary sectional view taken on line 5—5 of Fig. 4. 65

Fig. 6 is a top plan view of the forming mechanism with parts broken away and parts shown in section in one of the stages of the operation.

Fig. 7 is a view similar to Fig. 6 in succeeding stages of the operation. 70

Fig. 8 is a fragmentary view of the twister and hook forming mechanism with parts shown in section and parts in side elevation showing the operation successive as to Fig. 7. 75

Fig. 9 is a sectional view taken on line 9—9 of Fig. 8.

Fig. 10 is a sectional view taken on line 10—10 of Fig. 9.

Fig. 11 is a fragmentary view taken on line 11—11 of Fig. 10.

Fig. 12 is a fragmentary sectional view taken on line 12—12 of Fig. 9.

Fig. 13 is a fragmentary sectional view taken on line 13—13 of Fig. 1. 85

Fig. 14 is a fragmentary sectional view taken on line 14—14 of Fig. 13.

Fig. 15 is a fragmentary view taken on line 15—15 of Fig. 1 with a part broken away. 90

Fig. 16 is a fragmentary view taken on line 16—16 of Fig. 1.

Fig. 17 is a fragmentary view taken on line 17—17 of Fig. 1.

The invention is illustrated as supported on a suitable bed 28 provided with suitable legs. Projecting upwardly from the bed are standards 29 and 30. A bracket 31 is secured to the standard 29 at its upper end and projected upwardly therefrom and provided 100

with the upwardly extended supported portion 32. A bracket 33 is secured to and projected outwardly from the standard 30 and provided with the upwardly extended supported portion 34, a journal 68 being formed at the outer end of the bracket 33. Journalized in the supports 34 and 32 are shafts 35 and 36. Journalized in these supports are also the shafts 37 and 38, 35 and 36, and the shafts 36 and 38 being connected intermediate their ends by the braces 39. Journalized in these supports 32 and 34 is the shaft 40 on which is fixedly mounted the pinion 41 meshing with the pinion 42 which is mounted on the stub shaft 43. A pinion 44 is mounted on the outer end of the shaft 45 and meshes with the gear 42 as does likewise the gear 41 (see Fig. 1 and Fig. 2). The shaft 45 is also journalized in the supports 32 and 33 and extends parallel to the shaft 40. The shafts 35 and 37 and the shafts 36 and 38 serve as stay-rods, and the shafts 35 and 37 are connected to the shaft 40 by means of the brace 46 and a similar brace serves to connect the shafts 36 and 38 and 45. Mounted on the shafts 40 and 45 at spaced intervals are feed rollers 47, the rollers on the shaft 45 being in registration with the rollers on the shaft 40.

Guide plates 49 and 50 are extended vertically and through these guide plates extend the shafts 37 and 38, 40 and 45, 35 and 36. (See Fig. 1, Fig. 3, and Fig. 15.) The guide plates 49 and 50 are positioned opposite each other, and spaced apart to provide a tortuous space 52 the twisting of the space being determined by the outline of the plates themselves. These plates serve as a hopper or a support for strips of wire which are placed thereon and the wire is permitted to pass down into the space or passage 52 which has the angularly turned discharge portion 53 from which the wire 56 is prevented from passing by means of the plunger 54 which is normally held by the spring 55 in outwardly pressed position to engage the strip of wire 56. The shafts 35, 36, 37 and 38 extend through end plates 57 and 58. These end plates extend downwardly for a portion of the distance of the plates 49 and 50. Positioned below and in alignment with the plates 57 and 58 are the lower end plates 59 and 60 which have the beveled inner faces so as to direct the wire strips inwardly and cause their longitudinal movement to the proper position and maintain them properly centered relatively to the forming mechanism while being fed from the passage 53 to the forming mechanism. Extended through the supports 34 and 32 is a shaft 61 on which are fixedly mounted the feeding arms 62 each having a notch 63 formed in the outer edge of its free end. The construction is so arranged that as the shaft 61 is rotated these feeding arms will move into the full line position shown in Fig. 15 and upon continued

rotation move downwardly into the dotted line position shown in Fig. 15 carrying the strip of wire in the notch 63.

The shaft 61 is provided exterior of the supporting member 34 with a sprocket wheel 64 adapted to rotate therewith. This sprocket wheel 64 is connected by the chain belt 65 to a sprocket wheel 66 fixedly mounted on the shaft 67 which is journaled on the support or standard 30 and also in the journal 68 secured to and projecting outwardly from the shaft 67 is the eccentric arm 69 connected by the pitman 70 to the rocker link 71 which is fixedly mounted on the shaft 43. Fixedly mounted on the shaft 67 is the pinion 72 meshing with the gear 73 which is fixedly mounted on the shaft 74. Fixedly mounted on the shaft 74 intermediate the standards 29 and 30 are the drum forming discs 75 and 76 (see Fig. 1 and Fig. 2). The gear 73 meshes with the gear 77 mounted on the shaft 78 on which, for controlling the rotation of the gear 77, is mounted a clutch 79 operated by the lever 80. A gear 81 meshes with a gear 82 mounted on the shaft 83. A pulley 84 mounted on the shaft 83 is connected by the belt 85 to the pulley 86 which is mounted on the shaft 87 of the electric motor 88. The construction is such that upon an operation of the motor 88 the various gears will be set into rotation and the shafts 40 and 45 rocked through the oscillating action of the pitman 70. These shafts 40 and 45 are rocked in opposite directions as a single gear 42 serves to actuate them. In this way the rollers 47 serve to separate and feed individually, the strips of wire into the space or passage 52. At the same time that the oscillation of the rollers 47 is effected, the gear 73 is rotated so as to rotate the disc 75 and 76. At the same time also the shaft 61 is rotated so that the feeder arm 62, during each revolution of the shaft 61 will feed from the discharge portion 53 of the space one of the strips of wire. In the embodiment of the invention which I have shown I have illustrated four sets of forming mechanism carried by and rotating with the drum forming discs 75 and 76. The gearing to the shaft 61 is such that the shaft will rotate four times during each revolution of the shaft 74.

Each of the forming mechanisms is mounted on a bed or plate 89 which is mounted on the discs 75 and 76. Mounted on the upper surface of each of these beds or plates 89 are blocks 90 and 91 in each of which is formed a slot 92 into which the wire strip is delivered by the feeding arms 62, the wire strip passing from the feeding arm 62 into this slot 92. A forming nose 93 is formed on each of the blocks 91 and on the upper face of the blocks a recess 94 is provided in which is positioned a roller or forming stud 95. The portion of the wire which is engaged between the forming noses 93 on each of the plates

or beds may be termed the base of the garment hanger to be formed. As shown in Fig. 6 there is inwardly offset a portion of this base 96. Extended through the blocks 90 and 91 is a shaft 97 (see Fig. 5) provided with a head 98 cut away to provide the separated quadrants 100 and 101 (see Fig. 6). These quadrants being separated by forming each other by a space sufficient for the base 96 of the garment hanger therein. Before the forming operation, that is, when the wire is being fed from the feeding arm 62 the space is in alignment with the slot 92 which forms a continuation thereof. Fixedly mounted on the bottom of each of the shafts 97 or pins 97 is a segment 102 (see Fig. 4 and Fig. 5). On the pin or shaft 97 which corresponds to the pin or shaft 97 is a segment 103. Meshing with the segment 102 is a rack bar 104 which is connected to the rod 105, this rack bar being slidably mounted and riding in a guide 106 mounted on the under surface of the plate 89. The end of the rack bar is guided in its movements by engaging in a channel 108 formed in the guide bracket 107. A roller 109 is mounted on the outer end of the rack bar 104 and serves to engage the face of the cam 110 which projects inwardly from the face of the standard 30. The rack bar 104 engages the segment 102 at one side and at the side opposite to which the segment 103 is engaged in meshed relation by the rack bar 112 which is also attached to the rod 105 and which rides in the guide 111 secured to the under side of the plate 89. The construction is such that in the forming operation after the wire has been fed to the slot 92, the roller 109 will ride upwardly on the cam 110 and the heads 98 twisted into the position shown in Fig. 6 so as to provide the inward offset of the base 96 intermediate its ends. A bending arm 113 from the upper surface of the upper end of which projects a stud 114 is fixedly mounted on the shaft 115 on which is fixedly mounted the bevel gear 116 meshing with the bevel gear 117 fixedly mounted on the shaft 118. This shaft 118 is provided on its upper end with a square portion provided with flat faces 188 adapted in certain positions of movement of the discs 75 and 76 to engage the flat guide strip 189 which is mounted on the inner surface of the standard 30. This guide strip, commences where the segment strip 190 ends; the construction being such that at the position of rotation of the discs 75 and 76 at which the gear 192 will mesh with the segment strip 190, the shaft 118 will be rotated and when the flat 188 of the shaft 118 is in engagement with the strip 189 a rotation of the shaft 118 will be prevented. Mounted (see Fig. 4 and Fig. 5) on the shaft 118 is a bevel gear 119 meshing with a gear 120 fixedly mounted on the shaft or pin 121 on which is fixedly mounted the bending arm 122 projected up-

wardly from the upper surface of the outer end of which is a stud 123. The construction is such that if the roller 109 has risen on to the lobe of the cam 110, the flat 188 will ride off the strip 189 and the gear 192 will engage the segment strip 190 causing a rotation of the shaft 118 and an inward swinging of the bending arms 122 and 113 from the full line position shown in Fig. 1 to the full line position shown in Fig. 7, Fig. 6 illustrating various positions of these bending arms. The ends of the wire strip are thus brought around the forming noses 93 to give to this structure the desired outline and shape at the ends of the base 96.

Mounted on the plate 89 is the L-shaped plate 125 (see Fig. 1 and Fig. 14), this L-shaped plate or block being mounted on the projection 124 which extends upwardly from the upper surface of the plate or bed 89 (see Fig. 13). The plate 125 is mounted to provide a space 126 into which one of the ends of the wire is forced by the bending arms 122 and 113 so that this wire end engages the head 127 on the pin 128. The other end of the wire will engage the collar 129 formed on the pin 130 which is slidably mounted. A recess 129' is formed in the inner face of the plate 125 to actuate the collar 129. Rotatably mounted on the pin 130 is a bending wheel 131 which is in spaced relation to the bend wheel 132 which is rotatably mounted on the shaft 133. These bending wheels have each peripheral grooves 135 and 136 and are held in alignment in their axial movement by the yoke 134 which engages in the peripheral grooves of these wheels. Fixedly mounted on the lower end of the shaft 133 is a segment 144 (see Fig. 4 and Fig. 13), this segment is adapted to mesh with the rack bar 145. A rod 137 is connected pivotally to an extension 138 which rides in the channel 140 of the guide bracket 139 and which is provided on its outer end with a roller 141 adapted to engage a cam 141' projecting inwardly from the face of the standard 30. The inner end of the rod 137 is pivotally connected to one end of a bell crank 142 which is pivotally mounted on the bracket 143. The bell crank is provided with the yoke having rollers 146 engaging in a peripheral groove formed in a collar 146' mounted on the shaft 133. Immediately upon the inward movement of the bending arms 113 and 122 to the positions shown in Fig. 7 the rod 137 is moved axially through the engagement of the roller 141 with the cam 141' so that the bell crank 142 is rocked to move the shaft 133 axially upwardly. The wheels 131 and 133 mesh with each other as shown in Figs. 6, 7, and 8, and upon this upward movement of the shaft 133 the wire ends are positioned inwardly of the projections 150 and 151 which extend upwardly from the upper face of the wheels 131 and

132 and which are formed with flat faces on one side as clearly indicated in Fig. 7 and Fig. 8. The pinion 144 meshes with the rack bar 145 which is connected to the rod 147 adapted to ride in the guide bracket 148 and which carries on its outer end the roller 149 adapted for engagement with the cam 149'. Immediately following the rockable movement of the bell crank 142 the arm 147 is moved axially to effect a rocking or rotation of the shaft 133 so as to bring the formed wheels 131 and 132 into the position shown in Fig. 7, thus the ends of the wire are extended in parallel relation in cross engagement to each other and one of the ends extends beyond the other. To prevent the ends whipping beyond the proper point upon their movement into engagement with the head 127 into the collar 129, the pivotally mounted dog 152 is provided.

Prior to the movement of the members 151 and 150 from the position shown in Fig. 7 to the position shown in Fig. 6, the dog 152 is brought into engagement with the trap 25 153 and tilted into the position shown in dotted lines in Fig. 14.

Mounted in and projecting outwardly from the bed 89 is a bracket 154 which serves as a journal for the shaft 155 extending through the bearing formed in the disc 75. A gear 156 is fixedly mounted on the outer end of the shaft 155. On the inner end of the shaft 155 is fixedly mounted a bevel gear 157, meshing with the bevel gear 158 mounted on the shaft 159 (see Fig. 1, Fig. 8, and Fig. 10). Fixedly mounted on the shaft 159 is a gear 160 positioned within the gear housing 161. Meshing with the gear 160 is a twisting mechanism in the form of a gear 162 which is provided with the central or hub portion 163 having the narrow slot 164 radiating outwardly. The lower portion of this slot 164' is widened. A shaft 165 (see Fig. 8 and Fig. 4) is provided intermediate its ends with the block 166 having teeth formed on one side to provide a rack bar adapted to mesh with the rollers 167 mounted in spaced relation on the gear box 161. A roller 169 is mounted on the block 166 and adapted to engage the arm 170 which is rotatably mounted by the pin 172 on the support 171 which projects from the bracket 154. A roller 165' is mounted on the end of the shaft 165 and adapted to engage the cam 55 165''. Upon the riding of the roller 165' on to the peak of the cam 165'' the gear housing 161 will be rocked on the shaft 159 as a center to move the gear 162 so that the parallel and engaging ends of the wire will be engaged in the slot 164. A segment 156' is mounted on the standard 29 and this segment 156' now engages the gear 156 causing a rapid rotation of the shaft 159 which will effect a rotation of the gear 162 and twist the wire as it is shown twisted in Fig. 8. At the same time

the rocking of the member 170 will effect a rocking of the arm 173 which is pivotally mounted on the pin 172 (see Fig. 8 and Fig. 11). This rocking of the arm 173 being effected by the engagement of the roller 169 with the inclined surface 170' of the bar 170. Projecting inwardly from the arm 173 is a trunnion 174 and a similar trunnion 175 projects inwardly from the arm 170 (see Fig. 10 and Fig. 11) so as to engage between the collars 177 and 176 fixedly mounted on the shaft 178. Upon this rocking movement the shaft 178 is moved axially and the gear 179 which is non-rotatably mounted on the shaft 178 will be in engagement with the rack bar 184 which is attached to the rod 183 which is pivotally connected to the extension 185 and rides in the guide bracket 186 and which is provided on its outer end with a roller 187 adapted to engage the cam 187'. Carried by the shaft 178 is the forming plate 180 projecting outwardly of which is the forming disc 181 in spaced relation to the forming stud 182. Upon the axial movement of the shaft 178, the extended end of the wire will engage between the stud 182 and the former 181 and upon axial movement of the rod 183 this former will be rotated to form a hook 283 of the garment hanger.

All of the forming mechanisms which are mounted on the rotatable discs are similarly formed and similarly operated so that a single set of cams will serve to operate as forming mechanism as none of the forming mechanisms will be performing the same operation at the same time. Positioned at such a point on the discs as to engage the various rollers and restore them to their initial position of operation are guide strips 191 which engage rearwardly of the rollers and serve to bring them outwardly from their inwardly pressed positions so as to ride on the surface of the supports 29 and 30, the garment hanger being removed from the forming mechanism at the same time.

It will be noted that the forming mechanism is rotated as this is the most compact form of construction but it is believed obvious that horizontally or vertically positioned cams arranged in successive order co-operating with a movable forming mechanism might be employed with equal effect.

While I have illustrated and described the preferred form of my invention, I do not wish to limit myself to the precise details of structure shown but desire to avail myself of such variations and modifications as may come within the scope of the appended claims.

Having thus described my invention what I claim as new and desire to secure by Letters Patent is:

1. In a forming machine of the class described: a rotatable carrier, a wire receiving portion; a bending mechanism for bending said wire inwardly to provide an inwardly

- projecting offset intermediate its ends; a pair of bending arms for bending the ends of said wire intermediate toward each other; a bending mechanism for bending the inwardly bent ends into parallel relation on a twisting mechanism for twisting said ends about each other; a hook forming mechanism for forming a hook on one of said ends; and means for actuating said bending mechanism, said bending arms, said twisting mechanism, and said hook forming mechanism upon rotation of said carrier.
2. In a garment hanger forming machine for forming garment hangers from bendable material, bending arms for shaping said wire to the form of a garment hanger; a twisting mechanism for twisting the ends of said wire together; a hook forming mechanism for forming a hook on one end of said wire; a bed for supporting said bending and forming and twisting mechanism; a rotatable carrier for supporting said bed; means for rotating said carrier; and means for actuating said mechanism upon rotation of said carrier.
3. In a forming machine of the class described for forming articles from bendable material, a rotatable carrier; movable bending arms mounted on said carrier for shaping the wire to the form desired; a twisting mechanism mounted on said carrier for twisting the ends of the wire together; a hook forming mechanism mounted on said carrier for forming a hook on one end of said wire; means for rotating said carrier; and means for moving said shaping arms and actuating said twisting mechanism and said hook forming mechanism upon rotation of said carrier.
4. In a forming machine of the class described for forming articles from bendable material, a rotatable carrier; movable bending arms mounted on said carrier for shaping the wire to the form desired; a twisting mechanism mounted on said carrier for twisting the ends of the wire together; a hook forming mechanism mounted on said carrier for forming a hook on one end of said wire; means for rotating said carrier; means for moving said shaping arms and actuating said twisting mechanism and said hook forming mechanism upon rotation of said carrier; a receptacle for pieces of wire; and means for individually feeding the pieces of wire to said mechanisms upon rotation of said carrier.
5. In a forming machine for forming articles from bendable material, a rotatable carrier; a pair of slot bearing blocks mounted on said carrier in spaced relation adapted for the reception of a piece of wire, each of said blocks having a forming nose thereon; a pair of bending arms movably mounted on said carrier adapted for movement into position for forcing the wire around said bending nose for shaping the wire to the form desired; and means operable upon rotation of said carrier for shaping the wire
- of said carrier for moving said arms into shaping position.
6. In a forming machine for forming articles from bendable material, a rotatable carrier; a pair of slot bearing blocks mounted on said carrier in spaced relation adapted for the reception of a piece of wire, each of said blocks having a forming nose thereon; a pair of bending arms movably mounted on said carrier adapted for movement into position for forcing the wire around said bending nose for shaping the wire to the form desired; a twisting mechanism for twisting the ends of said wire together; and means operable upon rotation of said carrier for moving said shaping arms to shaping position and for actuating said twisting mechanism.
7. In a forming machine for forming articles from bendable material, a rotatable carrier; a pair of slot bearing blocks mounted on said carrier in spaced relation adapted for the reception of a piece of wire, each of said blocks having a forming nose thereon; a pair of bending arms movably mounted on said carrier adapted for movement into position for forcing the wire around said bending nose for shaping the wire to the form desired; a twisting mechanism for twisting the ends of said wire together; a hook forming mechanism for forming a hook on one end of said wire; means for rotating said carrier; and means operable upon the rotation of said carrier for moving said arms to shaping position and for actuating said twisting mechanism and said hook forming mechanism.
8. In a forming machine for forming articles from bendable material, a rotatable carrier; a pair of slot bearing blocks mounted on said carrier in spaced relation adapted for the reception of a piece of wire, each of said blocks having a forming nose thereon; a pair of bending arms movably mounted on said carrier adapted for movement into position for forcing the wire around said bending nose for shaping the wire to the form desired; a twisting mechanism for twisting the ends of said wire together; a hook forming mechanism for forming a hook on one end of said wire; means for rotating said carrier; means operable upon the rotation of said carrier for moving said arms to shaping position and for actuating said twisting mechanism and said hook forming mechanism; a hopper for containing pieces of wire; and means for feeding the pieces of wire individually into engagement in said slots upon rotation of said carrier to a predetermined position.
9. In a garment hanger forming machine adapted for forming garment hangers from bendable material, a movable carrier, movable in a cycle of operation; movable means mounted on said carrier for shaping the wire

to the form of a garment hanger; a twisting mechanism carried by said carrier for twisting the ends of the wire together; a hook forming mechanism carried by said carrier
5 for forming a hook on one end of said wire; means for moving said carrier through its cycle of operation; and means for moving said first mentioned movable means and actuating said twisting mechanism and said hook
10 forming mechanism at predetermined positions of movement of said carrier through its cycle of operation.

10. In a forming machine of the class described, a movable carrier movable through a cycle of operation; means for moving said carrier through its cycle of operation; forming means mounted on said carrier for forming a wire to the shape desired; a twisting mechanism carried by said carrier for twisting
15 the ends of the wire together; a hook forming mechanism carried by said carrier for forming a hook on one end of said wire; and a cam means for moving said forming means and actuating said twisting mechanism, and said hook forming mechanism upon movement of said carrier through its cycle of
20 operation.

In testimony whereof I have signed the foregoing specification.

JOHN MOORE.
